STORM WINDOW CONSTRUCTION

George L. Farmer, Louisville, Ky.

Application July 24, 1957, Serial No. 673,928

6 Claims. (Cl. 20—53)

This invention relates to a device for holding the lower edge of a storm sash or the like.

An object of this invention is to provide a readily operated device which can hold the lower edge of a storm sash open or closed.

A further object of this invention is to provide a sash holder which includes an elongated main arm pivotally mounted on the sash which can swing between an open position in which the elongated arm engages a stud member which is attached to the casing of the window and holds the sash open and a closed position in which a track on the elongated member adjacent the pivot thereof engages and grips the stud to hold the sash closed.

The above and other objects and features of this invention will in part be apparent and in part be obvious to those skilled in the art to which this invention pertains from the following detailed description, and the drawing, in which:

Figure 1 is a view in vertical section of a window opening having a double hung window equipped with a storm sash held in open position by a pair of sash-holding devices constructed in accordance with an embodiment of this invention;

Fig. 2 is a view in section taken on the line 2—2 in Fig. 1, one of the sash-holding devices being shown in released position in dotted lines;

Fig. 3 is an enlarged fragmentary view in horizontal section showing the device in position for holding the storm sash in closed position;

Fig. 4 is an enlarged fragmentary view in section taken along the line 4—4 in Fig. 3;

Fig. 5 is a view in section taken on the line 5—5 in Fig. 4;

Fig. 6 is a view in section taken on the line 6—6 in Fig. 4;

Fig. 7 is an enlarged fragmentary view of one end of the arm of the device shown in position for holding the storm sash in open position;

Fig. 8 is an enlarged fragmentary view of a portion of the device shown with the storm sash closed preparatory to locking the sash in closed position; and

Fig. 9 is a fragmentary view in horizontal section showing a screen equipped with a similar device.

In the following detailed description, and the drawing, like reference characters indicate like parts.

In Figs. 1 and 2 is shown a window opening 10 provided with a casing having side members 12 and 14, a stool 16, and a lintel 15. Upper and lower sash are indicated at 17 and 18, respectively. The upper and lower sash run in channels 19 and 21 in the usual manner. The outer guides for the track of the upper sash are formed by molding strips 22 and 23 which are ordinarily referred to as blind stops. A storm sash 24 having a glass sheet 25 is hinged to the lintel 15 by hinges 26. The storm sash may be held in open position, as shown in Figs. 1 and 2 by sash-holding devices indicated at 27 and 28.

Details of construction of one of the sash-holding de-

2

vices are shown in Figs. 3 to 8 inclusive. As shown most clearly in Figs. 4 and 5, the sash-holding device 27 includes an elongated main arm 29 which is pivotally mounted on a hinge plate 31 by a pivot 32 (see Figs. 3 and 4) adjacent one end of the arm 29. The hinge plate 31, in turn, is pivotally attached to another hinge plate 33 by a pivot pin 34. The plate 33 is rigidly attached to a side frame member 36 of the storm sash 24. As shown, the arm 29 swings about its pivot 32

10 in a plane parallel to the hinge plate 31.

When the storm sash is in open position, the arm 29 engages a stud member or screw 37 having an enlarged head. The stud or screw 37 extends into the blind stop 22, as shown most clearly in Figs. 3 and 7. When the storm sash is open, the head of the stud 37 is received in a bayonet slot 38 adjacent the free end of the main arm of the device. A catch 41, which is pivotally attached to the main arm, is provided with radial grooves 42 one of which receives the stud member 37 to hold the arm in place with the shank of the stud member in the narrow portion of the bayonet slot.

When the storm sash is to be closed, the catch 41 is swung away to release the stud member 37. An inwardly directed flange 43 on the main arm can be grasped 25 to swing the main arm inwardly to the position shown in dotted lines in Fig. 2 at which the main arm is released from the stud member. The main arm of the device 27 may be released in a similar manner. Then the storm sash is drawn to the closed position indicated in Figs. 3, 4 and 5. As shown in Fig. 1, the distance of the stud member from the lintel is equal to the distance from the upper edge of the storm sash to the pivot 32 of arm 29 so that, when the storm sash is closed, the pivot 32 and the stud member 37 are in registry. A track comprising 35 angle-shaped flanges 44 and 45 is mounted on one side of the main arm in registry with the pivot thereof. The flanges 44 and 45 are spaced to provide a slot 46 therebetween. When the sash is drawn to the position shown in Fig. 8, the flanges 44 and 45 register with the screw 40 37 and the screw is received in the slot 46 between the flanges with the screw head being in registry with the pivot of the main arm 29. As shown, the width of the slot 46 is greater than the diameter of the shank of the stud member, but less than the diameter of the head 45 thereof so that the stud member is held thereby. Then the arm may be swung downwardly to the position shown in Figs. 3, 4 and 5 in which the sash is latched closed. As the arm swings, the flanges of the track swing therewith to the Fig. 5 position at which the flange 45 can 50 engage the stud member 37 to hold the storm sash closed. As shown in Fig. 6, when the main arm is swung down to this position, the main arm is in alignment with the blind stop 22. As shown, the main arm is narrower than the blind stop so that the device does not interfere 55 with operation of the window sash. As shown most clearly in Figs. 3 and 4, the hinge plate 33 is attached to the frame of the storm sash in alignment with the track flanges 44 and 45 so that a minimum amount of space is taken up by the sash holding device.

The device has been described to this point with relation to a storm sash; however, a similar device may be used in connection with a window screen. In Fig. 9, a device 47 is shown. If desired, hinge plates 49 (only one of which is shown) may be attached to the sides of the screen frame. These hinge plates 49 may be identical in construction with those attached to the storm sash so that, when the hinge pins are withdrawn, the main arms and associated parts of the devices may be used both with a storm sash and with a screen.

The devices described above and illustrated in the drawing are subject to structural modification without departing from the spirit and scope of the appended claims.

Having described my invention, what I claim as new, and desire to secure by Letters Patent is:

1. A sash holder which comprises a hinge plate for attaching to a side of the frame of a sash, another hinge plate pivotally connected to the first mentioned hinge plate, an elongated main arm pivotally attached to the other hinge plate adjacent an end of the arm, the pivot of the main arm extending transversely of the pivot between the hinge plates and spaced therefrom, means on the other end of the main arm for engaging a stud mounted in the window casing for holding the sash open, and a track on the main arm in registry with the pivot thereof for receiving the head of the stud when the sash is closed, the track being adapted to grip the stud when the main arm is swung on its pivot into substantial parallelism with the window casing.

2. A sash holder which comprises a first hinge plate for attaching to a side of the frame of a sash, another hinge plate pivotally connected to the first mentioned hinge plate, an elongated main arm pivotally attached to the other hinge plate adjacent an end of the arm, the pivot of the main arm extending transversely of the pivot between the hinge plates and spaced therefrom, means on the other end of the main arm for engaging a stud having an enlarged head mounted in the window casing for holding the sash open, and a track comprising a pair of spaced flanges with a slot therebetween on the main arm in registry with the pivot thereof for receiving the head of the stud when the sash is closed, the flanges being adapted to receive the head of the stud in the slot to grip the stud when the main arm is swung on its pivot into substantial parallelism with the window casing.

3. The combination with a window casing, of a sash, means for hinging the upper edge of the sash to the upper edge of the window casing, a molding strip on the casing against which a side of the frame of the sash abuts when in closed position, a stud mounted in the molding strip spaced between the ends thereof, a hinge plate attached to one side of the frame of the sash, another hinge plate pivotally connected to the first mentioned hinge plate, an elongated main arm pivotally attached to the other hinge plate adjacent one end of the main arm, the pivot of the main arm extending transversely of the pivot between the hinge plates and spaced therefrom, the stud registering with the pivot of the arm when the sash is closed, means adjacent the other end of the main arm for engaging the stud to hold the sash open, and a track mounted on the main arm in registry with the pivot, the track being adapted to receive the stud when the sash is closed, the main arm and track being swingable on the pivot of the main arm into a locked position in which the main arm is substantially parallel to and aligned with the molding strip and the track grips the stud and holds the sash closed.

4. The combination with a window casing, of a sash, means for hinging the upper edge of the sash to the upper edge of the window casing, a molding strip on the casing, against which a side of the frame of the sash abuts when in closed position, a stud mounted in the molding strip spaced between the ends thereof, a hinge plate attached to one side of the frame of the sash, another hinge plate pivotally connected to the first mentioned hinge plate, an elongated main arm pivotally attached to the other hinge plate adjacent an end of the main arm, the pivot of the main arm extending transversely of the pivot be-

tween the hinge plates and spaced therefrom, the main arm swinging in a plane substantially parallel to the other hinge plate, the stud registering with the pivot of the arm when the sash is closed, means adjacent the other end of the main arm for engaging the stud to hold the sash open, and a track mounted on the main arm in registry with the pivot, the track being adapted to receive the stud when the sash is closed, the main arm and track being swingable on the pivot of the main arm into a locked position in which the main arm is substantially parallel to and aligned with the molding strip and the track grips the stud and holds the sash closed, the width of the molding strip being at least as great as that of the main arm.

15 5. The combination with a window casing, of a sash, means for hinging the upper edge of the sash to the upper edge of the window casing, a molding strip on the casing against which a side of the frame of the sash abuts when in closed position, a stud having an enlarged head
20 mounted in the molding strip spaced between the ends thereof, a hinge plate attached to one side of the frame of the sash, another hinge plate pivotally connected to the first mentioned hinge plate, an elongated main arm pivotally attached to the other hinge plate adjacent one
25 end of the main arm, the pivot of the main arm extending transversely of the pivot between the hinge plates and spaced therefrom, the stud registering with the pivot of the arm when the sash is closed, means adjacent the other end of the main arm for engaging the stud to hold
30 the sash open, and a track mounted on the main arm in registry with the pivot, the track comprising a pair of spaced angle-shaped flanges having a slot therebetween adapted to receive the stud when the sash is closed with the head of the stud held therebetween, the main arm and
35 track being swingable on the pivot of the main arm into a locked position in which the main arm is substantially parallel to and aligned with the molding strip and the track grips the stud and holds the sash closed.

40 6. A sash holder comprising a hinge consisting of two plates pivotally connected to each other, one of said plates being adapted to be pivotally secured to a side of a frame of a sash, the pivot of said two plates being normal to the axis about which the sash swings, an elongated main arm, one end of said main arm comprising a track, said 45 one end being pivotally connected to the other plate of said hinge and in constant engagement with a side thereof, there being a bayonet slot on the other end of said main arm for locking engagement to a single stud mounted on and extending into a window casing for holding the sash open, said arm and said other plate being pivotable about said one of the plates of the hinge inwardly from the window casing when the sash is in open 50 position to release said slot from the locking engagement, said track being in registry with the pivot of said main arm for receiving the head of the stud when the sash is closed, the track being adapted to grip the stud when the main arm is swung on its pivot into substantial parallelism with the window casing, and a catch pivotally attached to the main arm, said catch being adapted to 55 engage the stud when the stud extends through the bayonet slot.
